(57) **CLAIM**

The ornamental design for a luminaire, as shown and described.

DESCRIPTION

FIG. 1 is a bottom perspective view of a luminaire showing our new design;

FIG. 2 is a top perspective view thereof;

FIG. 3 is a side elevational view thereof, the opposite side being a mirror image;

FIG. 4 is an end elevational view thereof, the opposite end being a mirror image;

FIG. 5 is a top plan view thereof; and

FIG. 6 is a bottom plan view thereof.

FIG. 7 is a bottom perspective view of a luminaire showing an alternative embodiment of our new design;

FIG. 8 is a top perspective view thereof;

FIG. 9 is a side elevational view thereof, the opposite side being a mirror image;

FIG. 10 is an end elevational view thereof, the opposite end being a mirror image;

FIG. 11 is a top plan view thereof; and,

FIG. 12 is a bottom plan view thereof.

The suspension cables for the luminaire are shown broken away to indicate indefinite length.

In the embodiment of the luminaire shown in FIGS. 1-6, the broken line discs shown in FIGS. 1-4 represent ceiling plates, and the broken line rectangles shown in FIG. 2 represent area light sources such as OLEDs. The ceiling plates and area light sources shown in broken lines form no part of this embodiment of our claimed design.

In the embodiment of the luminaire shown in FIGS. 7-12, the broken line discs shown in FIGS. 7-9 represent ceiling plates, and the broken line rectangles shown in FIGS. 7-8 and FIG. 12 represent area light sources such as OLEDs. The ceiling plates and area light sources shown in broken lines form no part of this embodiment of our claimed design. The large broken line rectangles shown in FIGS. 8 and 11 are boundary lines; the area within the boundary lines forms no part of this embodiment of the claimed design.

1 Claim, 6 Drawing Sheets
